ED. MURREY, OF LINCOLN, NEBRASKA.

CLAM-SHELL BUCKET.

1,279,744.

Specification of Letters Patent. Patented Sept. 24, 1918.

Application filed November 6, 1917. Serial No. 200,482.

To all whom it may concern:

Be it known that I, Ed. MURREY, a citizen of the United States, residing at Lincoln, in the county of Lancaster and State of Nebraska, have invented certain new and useful Improvements in Clam-Shell Buckets; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to clam shell buckets, and has for its principal object to provide a bucket of that character wherein the shell or bucket sections are so mounted that an exceedingly wide reach is obtained, and 20 wherein the bucket closing and opening mechanism is constructed in such a manner that the hoisting power is applied therethrough equally to both sections of the bucket and a positive downward pressure is 25 placed thereon during the closing operation.

In accomplishing this object, I have provided improved details of structure, the preferred forms of which are illustrated in the accompanying drawings, wherein:—

30 Figure I is a side elevation of a bucket constructed according to the present invention; the bucket being shown in open position.

Fig. II is a longitudinal sectional view of 35 the same on the line II—II, Fig. IV, showing the bucket in open position.

Fig. III is a transverse sectional view on the line III—III, Fig. I.

Fig. IV is a plan view of the parts particularly illustrating the carrying frame and bucket operating levers.

Referring more in detail to the drawings:—

1 designates a horizontally disposed, rectangular frame wherein the bucket or scoop sections and their operating mechanism are mounted, and which, in its preferred construction, comprises opposite side beams 2—2', end beams 3—3' connecting the side beams, and intermediate beams 4—4' which are spaced slightly apart and extend longitudinally through the center of the frame and are attached at their opposite ends to the end beams 3—3' to add strength and

rigidity to the frame and supplement the side beams in supporting the bucket and its 55 operating mechanism presently described.

Erected centrally on each of the side beams of the frame are standards 5—5' which at their upper ends revolvably carry a transverse 60 shaft 6 for a purpose later described, and over the upper end of each standard curved plates 7 are fixed, the ends of which are provided with apertures 8 wherein the upper ends of anchor rods 9 are fixed; the lower 65 ends of said rods being extended to the opposite ends of the frame where they are attached thereto to form a lifting device whereby the strain on the frame under a load is distributed evenly over the frame, 70 and its balance maintained.

Supported transversely within the frame, and extending through the side beams 2—2' and intermediate beams 4—4' in paired relation at equal distances from the transverse 75 center of the frame, are the bucket section supporting shafts 10—10', and a pair of intermediate shafts 11—11', and revolvably mounted on said shafts between the beams 4—4' so as to be centrally located within the 80 frame is a gear train comprising a pair of wheels 12—12' at the outer ends of the train, and interposed gear wheels 13—13' of lesser diameter than the outer wheels; the wheels all being in mesh, and those of each pair 85 being equal in diameter so that they will move equally and simultaneously to carry the bucket sections apart or together in perfect balance relative to their suspension from the frame.

90 The bucket portion of the device comprises the paired scoop sections 15—15', which are formed in such a manner that when brought together they form a longitudinally separable semi-cylindrical carrier; the said sections 15—15' being pivotally suspended respectively by the shafts 10—10' by means of a plurality of S-shaped hanger arms 16, it being preferred to use four of such arms for the support of each bucket section, and 100 the same are disposed at opposite ends and at the centers of the sections with the two outer arms pivotally connected with the shaft by means of V-shaped bracket members 17—17', and the two intermediate arms 105 of each section are bolted to the opposite faces of the gear wheels 12—12', and the arms of each section are all connected re-

spectively by transverse shafts 18-18', which are extended through the ends of the said arms and through the wheels 12-12' so that revoluble movement of the wheels will 5 simultaneously move the bucket sections toward and from closed position.

To move the bucket sections on the pivoted mounting from an open to a closed position, I provide the wheels 13-13' with 10 actuating lever arms 20-20', which are pivoted on the shafts 11-11' at opposite sides of the wheels and are bolted thereto so that radial movement of the said arms from a substantially horizontal position, as 15 shown in Fig. II, to a vertical position, as shown in Fig. I, will revolve the wheels 13-13' and incidentally the wheels 12-12', meshing therewith to move the bucket sections together.

20 To effect this radial movement of the bucket closing arms, I provide a closing cable 22, which is attached at one end to a derrick or the like, (not shown) and extends over sheave wheels 23-23' revolubly carried 25 by the outer ends of the arms 20-20', and then upwardly to the derrick and suitable power or hoisting drums; the cable also operates over a sheave wheel 24, centrally mounted on the shaft 6 so that tension on 30 the cable moves the free ends of the arms radially upward to revolve the wheels 13-13' and 12-12' to close the sections of the bucket together, and will at the same time exert a downward pressure on the 35 frame through the shaft 6 and standards 5-5' until the closing operation is completed, thereby under normal conditions insuring a full bucket.

It is apparent that tension on the cable 40 22 will retain the bucket closed, and the load will not be dropped until this tension is relieved.

To open the bucket sections apart, I provide each with a plurality of cables 30 which 45 operate over rollers 31-31' at opposite ends of the frame, and are attached at their upper ends to a clevis 32 and at their lower ends to the outer ends of brackets 33 fixed to the 50 arms 16 and extending from the back of the bucket sections; the clevis being suspended from a cable 34 that operates over a pulley and derrick (neither shown) so that power may be applied therethrough when tension 55 on the cable 22 is slackened, to open the bucket sections quickly apart and deliver the load therefrom.

It will be seen that the cable 34 may be used for carrying the open bucket to loading position, and that when ready to load it 60 may be slackened and the tension applied on the cable 22 to close the sections together and carry the bucket to the place where it is desired to deposit the load.

By providing the device with a frame of 65 this character, wherein the sections are

spaced apart as shown, an exceedingly wide reach is permitted, which insures a full load at each operation, and by extending the cable 22 over the wheel on the shaft 6 a positive downward pressure will be exerted 70 on the frame during a closing operation of the bucket that will hold the bucket to the ground, and not tend to lift until the load has been taken up.

It is further apparent that by providing 75 the gear mechanism for actuating the sections of the bucket, both will move equally and simultaneously to maintain an even balance on the frame, and danger of losing any part of the load is eliminated.

Having thus described my invention, what I claim as new therein, and desire to secure by Letters Patent, is:

1. In a device of the character described, a frame, shafts mounted in said frame, a 80 pair of coöperating scoop sections suspended from said shafts; a train of intermeshing gear wheels mounted within said frame and adapted to actuate the scoop sections; and lever arms fixed to said gear wheels and operable under tension of a hoisting cable to close said scoop sections together.

2. In a clam shell bucket, the combination of a frame, paired inner and outer shafts mounted transversely of said frame, a pair 95 of coöperating scoop sections pivotally suspended from said frame by said outer shafts, a train of intermeshing gear wheels mounted on said shafts centrally of said frame; a pair of lever arms fixed to the inner pair of gear wheels, sheave wheels mounted at the outer ends of said arms, and a hoisting cable operating over said sheave wheels to move the arms together to simultaneously revolve the gear wheels and close the scoop sections together.

3. In a clam shell bucket, the combination of a horizontal frame, paired inner and outer shafts mounted transversely of said frame, hanger arms mounted on the outer paired shafts, coöperating scoop sections supported by said arms and adapted for movement under control of said supporting shafts toward and from each other, a train of intermeshing gear wheels mounted on 115 said shafts, a pair of lever arms fixed to the inner pair of gear wheels and adapted for extending horizontally in opposite directions when said bucket is open, sheave wheels mounted at the outer ends of said arms, and a hoisting cable extending over 120 said sheave wheels whereby the said arms may be drawn upwardly and together to revolve said gear wheels and move the scoop sections together.

4. In a clam shell bucket, the combination of a horizontal frame, standards mounted at opposite sides and centrally of said frame, a transverse shaft supported at the upper ends of said standards, a sheave wheel 130

mounted centrally on said shaft, paired inner and outer shafts mounted transversely of said frame, hanger arms mounted on the outer paired shafts, coöperating scoop sections supported by said arms and adapted for movement under control of said supporting shafts toward and from each other, a train of intermeshing gear wheels mounted on said shafts, a pair of lever arms fixed 10 to the inner pair of gear wheels and adapted for extending horizontally in opposite directions when said bucket is open, sheave wheels mounted at the outer ends of said arms, and a hoisting cable extending over said sheave wheel whereby said arms may be moved upwardly and together to revolve said gear wheels to move the scoop sections together.

5. In a clam shell bucket, the combination 20 of a horizontal frame, paired inner and outer shafts mounted transversely of said frame, hanger arms mounted on the outer paired shafts, coöperating scoop sections supported by said arms and adapted for movement under control of said supporting shafts toward and from each other, a train of intermeshing gear wheels mounted on said shafts, a pair of lever arms fixed to the inner pair of gear wheels and adapted for 25 extending horizontally in opposite directions when said bucket is open, sheave wheels mounted at the outer ends of said arms, a hoisting cable extending over said sheave wheels whereby the said arms may be drawn upwardly and together to revolve said gear wheels and move the scoop sections together, and cables attached to the outer sides of said bucket sections whereby 30

the latter may be drawn apart when tension is removed from the first named cable. 40

6. In a clam shell bucket, the combination of a horizontal rectangular frame, standards mounted at opposite sides centrally of said frame, a transverse shaft mounted at the upper ends of said standards, a sheave 45 wheel mounted centrally on said shaft, rollers mounted at the ends of said frame, paired inner and outer shafts mounted transversely of said frame, hanger arms mounted on the outer paired shafts, coöperating scoop sections supported by said arms and adapted for movement under control of said supporting shafts toward and from each other, a train of intermeshing gear wheels mounted on said shafts, a pair 50 of lever arms fixed to the inner pair of gear wheels and adapted for extending horizontally in opposite directions when said bucket is open, sheave wheels mounted at the outer ends of said arms, a hoisting cable extending 55 over said sheave wheels and over the first named sheave wheel whereby the outer ends of said arms may be moved upwardly and together to revolve said gear wheels to actuate the scoop sections together, and trip 60 cables attached at their lower ends to the outer sides of said scoop sections and extending over the rollers at the ends of said frame whereby said sections may be drawn apart to 65 deliver a load therefrom. 70

In testimony whereof I affix my signature.

ED. MURREY.
